UNITED STATES PATENT OFFICE.

CHARLES ALGERNON PARSONS, OF NEWCASTLE-ON-TYNE, ENGLAND.

MEANS FOR STIRRING GLASS.

Application filed October 17, 1922. Serial No. 595,129.

To all whom it may concern:

Be it known that I, CHARLES ALGERNON PARSONS, a subject of the King of Great Britain and Ireland, and residing at Heaton 5 Works, Newcastle-on-Tyne, in the county of Northumberland, England, have invented certain new and useful Improvements in and Relating to the Means for Stirring Glass, of which the following is a specification.

This invention relates to improvements in the manufacture of glass and more particularly to the stirring of optical glass.

According to the usual process adopted at 15 the present time, optical glass is melted in clay pots which are often formed with an integral top having a side opening or mouth through which the ingredients are introduced. When a pot has been filled and has 20 been heated for a sufficient period at a high temperature to incorporate thoroughly all the ingredients and to allow air bubbles to rise to the surface, the temperature is gradually lowered and the glass well stirred by 25 a cylindrical clay stirrer actuated by a water-cooled bar or tube introduced through the mouth of the pot. The stirrer, which is maintained in a substantially vertical position, is moved by hand or more generally by 30 mechanical power in a more or less circular orbit of any predetermined shape and position. The speed of motion of the stirrer is, however, limited, for if too great, air is entrained in the wake of the stirrer and in 35 consequence of this limitation the stirring is found in practice to be insufficient to secure complete homogeneity of the glass.

The object of the present invention is to remove this limitation and to secure a much 40 more thorough stirring of the glass than heretofore without the entrainment of air, or in other words, to enable a much greater power to be applied in the process of stirring.

With this object:—

The invention consists in imparting to the stirrer a rapid rotary motion about its own axis with or without a relatively slow orbital movement.

The invention also consists in a stirrer of 50 the kind set forth in the preceding paragraph, constructed from a simple or complex loop of metal tube.

The invention likewise consists in the improved form of stirrers hereinafter described or indicated.

Referring to the accompanying drawings:—

Figure 1 shows an elevation, for the most part in section, of a form of paddle stirrer and driving mechanism therefor,

Figures 2 and 3 being corresponding side and end views respectively, and

Figure 4 a section on the line 4—4 of Figure 1 as seen in the direction of the arrows; while

Figure 5 shows a modified form of the invention in which a loop-formed stirrer is employed,

Figures 6 and 7 being corresponding side and end views respectively.

Where desirable corresponding parts in the different forms of the invention are indicated by the same reference symbols.

In carrying the invention into effect according to the form shown in Figures 1 to 4, the clay stirrer, *a*, is of the usual cylindrical shape but provided with projections or paddles, *b*, which may be arranged in spiral formation as shown, the diameter of the stirrer at the point where it passes through the surface of the glass being as small as possible consistent with strength, so as to reduce the disturbance at this point to a minimum. The stirrer may be actuated in the usual manner from a water-cooled iron core, *c*, to which, according to the present invention, a rotary motion is imparted by bevel gear *d*, *d*, in the water-cooled head of the stirring rod or tube. This head may comprise a chamber, *e*, provided on the one hand with a tubular extension, *f*, serving for the accommodation of the driving shaft, *h*, and the water outlet, and on the other hand with a cap, *i*, to which the water inlet pipe, *k*, is secured. Passages, *m*, are also formed in the cap, *i*, to serve as an inlet for the cooling water. A hollow shaft, *n*, to which the stirrer proper is attached, is cooled in the manner shown by an inner tube, *o*, arranged in a space, *r*, of larger diameter so as to leave an annular recess for the return flow which finds an outlet by way of the aperture, *s*, registering with a similar aperture, *t*, in a sleeve, *u*, surrounding the shaft, *n*, and driven from one of the bevel

wheels, *d* by a pin, *v*, the sleeve, *u*, serving as shown to take the weight of the stirrer itself. The course of the cooling water is indicated by the arrows, and it will be seen that after entering through the pipe, *k*, and passages, *m*, in the cap, *i*, it passes down the centre tube, *o*, and returns through the surrounding annular space and by way of the apertures, *s* and *t*, to the interior of the chamber, *e*, and thence through the outlet passages, in the cap, *i*, to the annular space formed by the clearance between the tube, *f*, and the driving shaft, *h*.

In order to attach the stirrer proper, its head, *w*, is formed of square shape to correspond with a square box or socket, *x*, attached to the shaft, *n*, a clip, *z*, being provided to engage beneath the shoulder, *2*, of the square head of the stirrer so that it may be attached to the box, *x*.

Alternatively, the stirrer, *a*, may be made entirely of clay and actuated from a water-cooled socket rotated by any suitable means.

Instead of the clay stirrer described above, a water-cooled stirrer made of a suitable metal such as steel may be used. Such a stirrer may be of any suitable form, but generally, as shown in Figures 5 to 7, I prefer to construct it as a more or less helical loop, 3, of solid drawn steel tube, the two ends of the loop being brought close together as shown in Figure 5 and inserted into the end of the shaft, *n*, near the surface of the glass so as to secure a low velocity of motion at this point, while the loop is wide below so that the tube may move with a high linear velocity in the body of the glass. The shaft, *n*, is provided, as shown in Figure 3, with ducts 4 and 5 for the circulation of the cooling water, the course of which will be evident from the arrows without further description.

The mechanism for rotating the loop may conveniently be the same as that already described in relation to the clay paddle.

The complex form of loop illustrated is

well adapted for securing a thorough mixing of the upper and lower layers of the glass, but in some cases the loop may be of simpler form and lie in one plane.

In order to secure the best results, the stirrer in addition to a motion of rotation about its own axis is also given a slow orbital movement by any convenient mechanism such as is now employed or otherwise.

The general design of the stirrer whatever its precise form is such as to secure the maximum strength for the transmission of the greatest amount of power for the effectual stirring of the glass.

Although I have described certain forms of the invention in detail by way of illustration of its general character, I wish it to be understood that I do not restrict myself to such specific forms, as the latter can be modified to a large extent without exceeding the scope of the invention.

Having now described my invention, what I claim as new and desire to secure by Letters Patent is:—

1. For use in the manufacture of glass, a stirrer with means for giving thereto a rotary motion about its own axis and an orbital movement, substantially as and for the purposes described.

2. A stirrer as set forth in claim 1, including a loop of metal tube, substantially as described.

3. A stirrer as set forth in claim 1, including a loop of metal tube, in which cooling water is circulated through the loop-formed stirrer, substantially as described.

4. Driving mechanism for a stirrer as set forth in claim 1, comprising a chamber bevel wheels within the chamber and a passage for the circulation of cooling water passing through one bevel wheel substantially as described.

In testimony whereof I have signed my name to this specification.

CHARLES ALGERNON PARSONS.
